UNITED STATES PATENT OFFICE

2,496,757

URN BAG RETAINER

Edward H. Siefing, Chicago, Ill.

Application September 6, 1946, Serial No. 695,232

1 Claim. (Cl. 210—162)

1

My invention relates generally to coffee-urns, but it has more particular reference to a structure for holding and supporting the bag used in these urns, which said structure is adapted to maintain the bag in a spread manner by ring-shaped members, and preferably resting upon or in different positions relative to the urn jar.

In designing my present article, I have eliminated and overcome many of the objections and disadvantages which are inherent in the structures that have heretofore been used. I have provided the ring, that is threaded in the bag hem or heading, with a detachable bail that has a hand-grasp by which the bag may be handled when inserting it into or removing it from the urn, and I have also provided the above structure with means for spreading the lower or bottom portion of the bag. These parts made of wire may be metal strips or other suitable material that is preferably bent into the desired shape. The ring, the bail and the bag spreader I prefer to form as an integral unit.

In connection with the novel ring and spreader for the bag, I have provided a novel frame adapted for co-action with said ring and spreader for supporting the structure within the urn in a manner that will raise the bottom of the bag to a plane above the level of the brewed coffee in the jar inside the urn. This supporter may also be formed from wire, metal strips or other suitable material that is shaped to constitute a unit that co-acts with the other part of my device.

Primarily, the object of my present invention is the provision of an urn bag holder and supporter that is effective and dependable in operation, and which has no moving or hinged parts to get out of order. Another and equally important object is to provide a device of this character that may be readily produced at a very small manufacturing cost. Further objects of my invention are to provide a device for urn bags that is novel in construction, is made of sturdy parts, is dependable in use, and which may be assembled readily and quickly with the urn bag and the urn.

I prefer to carry out my invention and to accomplish the numerous objects thereof in substantially the manner hereinafter fully described, and as more particularly pointed out in the claims, reference being herein made to the accompanying drawings that form a part of this specification.

In the drawings:

Fig. 1 is a perspective view of my improved retainer device for urn bags.

Fig. 2 is a vertical fragmental section of an urn showing my invention applied thereto; and

Fig. 3 is another vertical fragmental section showing the supporter structure removed, and

the ring and spreader resting upon the urn jar.

The drawings, it will be understood, are more or less schematic for the purpose of disclosing a typical or preferred form in which my invention may be made, and in said drawings I have employed the same reference characters to designate like parts wherever they appear throughout the several views.

It is a purpose of my invention to form the ring and the bail out of a single length of stout yieldable wire, strip metal or the like, which is herein referred to as a strip or length of material in order to avoid confusion of terms. It will be appreciated that the structures may be fabricated or formed from any convenient material without departing from the principles of my invention.

Referring to Fig. 1, it will be seen that the strip is bent to provide a split ring 5 with a hollow coil 6 at one side of the split. The coil 6 is adapted to receive the end 7, which is offset inwardly of the ring at the end of the piece of material at the opposite side of the split, and frictionally retains the proximate ends of the ring together in a telescopic manner. The end of the split ring containing the offset end is shown detached from the hollow coil in dotted lines in Fig. 1. A further disclosure of the connection between the ends of the split ring will be found in my pending application for patent on Retainer, Serial No. 601,294, filed June 23, 1945 (now abandoned).

The bag 8 is preferably of suitable woven material such as used in coffee urns for making drip coffee. The bag is provided with a tubular hem or heading 9 at its mouth or upper edge to receive the ring 5. In assembling the bag upon the ring, the free end 7 of the ring is inserted through a transverse entrance slot in the tubular hem 9, and the bag is then threaded on until it extends entirely around the ring. The end 7 of the ring is then inserted into the coil 6 and thus held in place.

After forming the coil 6, the strip is extended preferably diametrically toward the opposite side of the ring 5 to provide a bail 10. A short distance from each end the bail is provided with upwardly extended oblique portions 11 that incline towards each other, and between these inclined portions the strip is formed with the reverse bends 12 that are connected by straight longitudinally disposed portions 13 that are preferably parallel to each other, and which together constitute a handle or hand-grasp by which the ring is manually held. At the free end of the bail, which is opposite the coil 6, the strip is provided with an upturned hook 14 that is adapted to engage the adjacent portion of the ring to detachably hold the bail in position.

When the end 7 of the ring has been inserted into the coil 6, the hooked end 14 of the bail is

engaged with an adjacent portion of the ring, which may be done by compressing the ring slightly so that the hook will pass beyond the ring.

When being used to brew coffee, the bag has a tendency to sag downwardly at its bottom, and thus cause an uneven or irregular distribution of the ground coffee in the bag. In order to overcome this inherent tendency, I have provided novel means for distending the bag bottom and for maintaining it in a nearly level plane, especially while in use. This I accomplish by providing a spreader which extends down into the bag from the ring structure. As shown, the spreader comprises a strip or length of material formed into a ring 15, preferably of less diameter than the upper ring 5 that is inserted into the bag hem. This spreader or second ring 15 is spaced from the first ring a distance substantially the depth of the bag so that said spreader ring will tend to maintain the bag in its normal shape, even while the wet ground coffee is in the bag. The strip forming the spreader ring 15 is preferably provided with oppositely disposed upstanding loops 16 which project up toward and pass around the end portions of the bail between the oblique portions 11 and the ends of the bail. These loops 16 have side-by-side portions that are preferably united to each other by brazing or otherwise, and the portions that pass around the bail are also similarly treated to provide rigidity to the structure.

When a small quantity of coffee is being brewed, the level of which will not reach the bottom of the bag in the urn, the ring 5 may be placed directly upon the top of the usual porcelain or glass jar 17 that receives the brewed coffee. However, in many establishments it is the practice to prepare a large quantity of coffee at a single brew so that when the brew is finished the jar 17 will be completely filled. Thus the lower portion of the bag will be submerged in the prepared coffee and will result in the production of a poor beverage.

I have overcome this defect by providing, as a part of my bag holder, a novel supporting device for the bag ring and spreader which will raise the structure to a position in the urn where the bag will be free from the liquid coffee in the jar. This device embodies upper and lower annular members 18 that are preferably of less diameter than the ring 5, but greater in diameter than the spreader, so that the latter with bag may be disposed inside said members 18. These annular members are secured to and connected by uprights 19 that are formed with lateral shoulders 20 near their lower ends to support the lower annular member. The annular members retain the uprights 19 in spaced apart relation. The upper ends of these uprights extend over the upper annular member 18, and are provided with outwardly disposed lateral lips 21 that project outwardly far enough to provide support for the bag ring 5. The shoulders 20 constitute means which engage and rest upon the top edge or rim of the jar 17, and the lower ends 22 of the uprights 19 are long enough to extend down into the jar against the inner surface thereof. The supporting device is first positioned in the urn in the manner just described, and then the combined ring and spreader, with the bag thereon, is placed in the cage-like support as shown in the drawings, with the upper portion of the bag

overlying the upper annular member of the supporting cage. This has a tendency to tighten and lift the bag, whereby the bottom of the bag is maintained taut against the spreader element. Thereafter the ground coffee is deposited in the bag according to the usual practice. The structure thus assembled for use is readily accommodated in the top of the urn, because in standard construction of urns the lid is usually a deep dome-shaped member. When the ring and spreader are used without the supporting cage, the upper portion of the bag will overlie the lip of the jar, tending to hold the bag taut and lift it to a certain extent, as above described. In making the ring and spreader, the loops 16 may be of varied lengths according to the service required, or they may be made adjustable in construction to permit its use in bags of different depths.

From the foregoing explanation, it will be seen the two units of the structure may be fabricated out of wire or an elongated strip of material, and the parts thereof may be brought into interengagement and be assembled with the bag and placed in the urn in a very quick and dependable manner. Of course, the present form and construction may be modified without departing from the principle involved. It will be understood, therefore, that the accompanying drawings and the herein description are given for the purpose of clearness of understanding only, and no unnecessary limitations are to be understood therefrom.

What I claim as new and desire to secure by Letters Patent is:

The combination of an open frame having an upper ring portion and a lower ring portion, radially extending shoulders on the lower ring portion of said frame adapted to be disposed upon the rim of an urn bag jar; lateral supporting elements at the upper ring portion of said frame extending radially therefrom, a bag ring adapted to receive an urn-bag disposed upon said frame and resting upon said lateral supporting elements, a bag spreader ring disposed normally in the lower ring portion of said frame below said bag ring, and upright rigid means connecting said spreader ring to said bag ring whereby said bag ring, said spreader ring and the bag are adapted to be bodily removed as a unit from said frame.

EDWARD H. SIELING.
